[57] CLAIM

The ornamental design for a golf glove, as shown and described.

DESCRIPTION

FIG. 1 is a perspective view of a golf glove showing my new design;

FIG. 2 is a top plan view in position of use, the broken line showing of a portion of a golf club is for illustrative purposes only and forms no part of the claimed design; FIG. 3 is a perspective view of the back side; and FIG. 4 is a perspective view of the palm side.

FIG. 4
